BY ATTORNEYS.

UNITED STATES PATENT OFFICE.

FRANCIS G. POWERS, OF MOWEAQUA, ILLINOIS.

CLOTHES-POUNDER.

SPECIFICATION forming part of Letters Patent No. 233,800, dated October 26, 1880.

Application filed August 16, 1880. (No model.)

To all whom it may concern:

Be it known that I, FRANCIS G. POWERS, of Moweaqua, in the county of Shelby and State of Illinois, have invented a new and Improved 5 Clothes-Pounder; and I do hereby declare that the following is a full, clear, and exact description of the same.

The object of my invention is an improvement in the class of atmospheric clothes-pounders—that is to say, pounders which are constructed with one or more chambers or cavities in which the air is alternately compressed and allowed to expand at each reciprocation.

The chief qualities which such pounders 15 should possess are maximum strength and lightness of structure combined with capability for allowing the passage of air with the greatest facility, so that they will be very durable and may be easily operated.

20 To these ends I have adopted the construction and combination of parts as hereinafter described, and shown in the accompanying drawings, in which—

Figure 1 is a central longitudinal section of 25 my improved pounder. Fig. 2 is a cross-section on line x x , Fig. 1. Fig. 3 is a plan view of the pounder inverted.

The body A of the pounder is preferably constructed of copper, and has a bell or bowl like 30 shape. The solid wooden handle B is detachable, being united to the tubular metal portion C by a screw-joint, a. As shown in the drawings, the part C is made of two sections, whose telescoped ends are soldered together.

35 The tube thus formed extends down into the body A, and contiguous to the upper side of the same is provided with an enlargement, b, which subserves two purposes—to wit, an air-chamber and a brace—for, in respect to the latter function, it will be noted the enlargement rests on and is firmly soldered to the body A.

The tube C has four vertical rows of perforations, c, in the portion that projects into the 45 body A, while holes d of greater individual or aggregate capacity are formed in the portion above the body. Just below the holes d is located a perforated diaphragm, constituting a valve-seat, D, to which a flap-valve, E, is 50 hinged, so as to open downward.

The valve is preferably constructed of brass

for sake of durability; but flexible material may be employed.

Within the body A are four plates, F, which are arranged radially to the tubes C. They 55 are straight on the inner edge, which is soldered to the tube C, and curved on the longer outer edge corresponding to the contour of the upper portion of the body A, to which they are also soldered. Their lower edges are inclined downward and outward. These plates form the strongest braces or supports for the tube and body of the pounder that can be employed consistently with due regard to lightness and the least obstruction to passage of 60 air—that is to say, they form a rigid connection between the tube C and body A, and also strengthen the latter, so that it cannot collapse or become broken down by long and hard use—a result which is of not infrequent occurrence 65 in this class of pounders.

The lower edges of the plates F are connected by a wire ring, G, for the purpose of enabling them to resist torsional action and other strains incident to use, and also to form 70 a guard which shall prevent the clothes from entering or becoming wedged in the cavities formed by and between the plates. Thus, by means of the plates F and ring G, I not only 75 form a very strong yet light interior stay and 80 re-enforce for the tube C and body A of the pounder, but also an effectual guard against the entrance of the clothes, and at the same time without in the least obstructing the free 85 passage of air.

The lower portion of tube C is made as 90 large as practicable, and in order to prevent the clothes entering the same I apply a coarse wire-screen, H, thereto, as shown.

In practical use the pounder is forced down 95 upon the clothes immersed in suds. The air contained in the body A and tube C is compressed, (since the valve G instantly closes and cuts off its escape in that direction,) and thus a quantity of water is forced rapidly through 95 the portion of the clothes directly beneath the pounder. The elasticity of the air which permits such compression also enables it to react and assist in forcing out of the chamber of the pounder the water which has entered it, and 100 as the pounder is raised the valve G drops and allows air to enter to supply the partial

vacuum in the body A, so that little water is lifted with the pounder.

In other devices of this class the great objection has been the obstruction to the passage of air, so that the water could not escape quickly, thus adding greatly to the labor of washing by increasing the weight to be lifted.

The course of air entering the pounder is indicated by arrows.

- 10 It will be noted that each of the four chambers into which the plates divide the part A has independent communication with the tubular handle C through openings e, and it results from such relation of parts that if the holes of one chamber should by any means become clogged the air will have free entrance into the other chambers, and hence the pounder will continue to operate successfully.
- 15

The use of the wooden part B of the handle 20 is very desirable, since it is less liable to break than tubular metal ones, and when wet is less slippery, so that it may be held firmly with an easier gripe. The adaptation for attachment and detachment of the handle B is also important, and the location of the air-inlets d as 25 near the body A of the pounder as practicable facilitates the easy entrance of air.

The function of the enlargement of the tube C may be further stated to be to allow the 30 largest practicable space for reception and

compression of air without unduly enlarging the size or increasing the weight and cost of the pounder.

What I claim is—

1. An atmospheric clothes-pounder having 35 a bell-shaped body, A, the tubular handle C, having perforations in its lower portion, the plates F, which are arranged radially and conform in outline to the space in the upper portion of part A, to which and to said tube their 40 respective outer and inner edges are soldered, and the stay and guard-ring G, which is attached to and connects the lower edges of the plates, all as shown and described, for the purpose specified.

2. In an atmospheric clothes-pounder, the combination, with the bell-like body A, of the tubular handle C, having a spherical enlargement, which rests on and is soldered to the top of said part A, thereby serving the double function of an air-chamber and a brace, as 50 shown and described, for the purpose specified.

The above specification of my invention signed by me this 12th day of August, 1880.
